UNITED STATES PATENT OFFICE.

THOMAS F. MAY, OF RUTH, NEVADA, ASSIGNOR OF ONE-HALF TO BARTON E. WALKER,
OF RUTH, NEVADA.

WRENCH.

Application filed March 17, 1925. Serial No. 16,164.

This invention, in general, relates to tools, and more particularly to an improved wrench having features which enhance its utility and efficiency.

5 An object of the invention is to provide an improved tool of this character, with which it is possible to obtain a powerful grip, either on a round or polygonal object.

Another object of the invention is to provide 10 a wrench of this nature with removable serrated jaw plates, so that the wrench will be capable of use as a pipe wrench or an ordinary monkey wrench.

Another object of the invention is to provide 15 a wrench wherein it is possible to extend the jaws further apart than in the ordinary structure.

A still further object of the invention is to provide a wrench of this nature, which 20 is simple in construction, reliable in operation, and use, strong, durable, easy to manipulate, not liable to readily get out of order, and otherwise well adapted for the purpose for which it is designed.

25 With the above and numerous other objects in view, as will appear as the description proceeds, the invention resides in certain novel features of construction, and in the combination and arrangements of parts 30 as will be hereinafter more fully described and claimed.

In the drawing:

Fig. 1 is an elevation of the wrench, embodying the features of my invention, showing 35 the lower portion thereof in section;

Fig. 2 is a perspective view of the fixed jaw;

Fig. 3 is a detail section, taken transversely through the wrench, substantially 40 on the line 3-3 of Fig. 1; and

Fig. 4 is a detail perspective, showing a modified form of the fixed jaw.

Referring to the drawing in detail, it will be seen that 1 designates a fixed jaw 45 and 2 a movable jaw. The fixed jaw 1 is provided with a shank 3 fixed to the ends of a slide frame 4 and to the parallel terminal ears 5' of an annular clamp member 5. The ends of the slide frame 4 and the terminal 50 ears 5' straddle the shank 3.

A tubular handle 6 is internally threaded and provided at its upper end with a shoulder 7. The clamp 5 is disposed about the handle 6 in abutment with the shoulder

7. The movable jaw 2 is provided with an 55 elongated shank 8, rectangular in cross section, and provided with threads for cooperating with the threaded interior 4 of the handle 6. This shank slidably extends through the frame 4 which is fixed to the shank 3 of the fixed jaw 1. It will thus be seen that by rotation of the tubular handle 6, the movable jaw may be moved away from or toward the fixed jaw.

The jaws 1 and 2 are provided with side 60 grooves as is shown at 10, in Fig. 2, in order that sides 11 of serrated plates 12 may be slidably engaged therewith. If desired, these jaws may be constructed, as is shown in Fig. 4, wherein a groove is shown having 70 a circular bottom, the groove being indicated by the numeral 13, and the bottom thereof by the numeral 14.

It is apparent that other changes may be 75 made in the details of construction and in the combination and arrangement of parts without departing from the spirit or scope of the invention as hereinafter claimed, or sacrificing any of its advantages.

The present embodiment of the invention, which I have described in detail retains all 80 of the features of advantage enumerated in the statement of the invention and above description, and other advantages which 85 will be evident to those using the tool and skilled in this art, without a more detailed description.

Having thus described my invention, what I claim as new is:

In a wrench structure, a tubular handle, 90 an annular shoulder formed exteriorly of one end of the tubular handle, a split ring disposed about the tubular handle adjacent the shoulder, a shank, parallel ears extending from the ends of the split ring straddling the shank and fixed thereto, a frame having its extremities straddling the shank and fixed thereto and extending over the shoulder so that said shoulder is disposed 95 between the frame and the ring, a fixed jaw on the shank, a movable jaw having a threaded shank disposed through the frame and through the handle so that upon rotation of the handle said movable jaw will be moved toward and away from the fixed jaw. 100

In testimony whereof I affix my signature,

THOMAS F. MAY.
